UNITED STATES PATENT OFFICE.

NICOLAI H. HILLER, OF CARBONDALE, PENNSYLVANIA.

WATER DISTRIBUTOR FOR CONDENSERS.

Application filed May 1, 1925. Serial No. 27,130.

To all whom it may concern:

Be it known that I, NICOLAI H. HILLER, a citizen of the United States, and resident of Carbondale, in the county of Lackawanna and State of Pennsylvania, have invented certain new and useful Improvements in Water Distributors for Condensers, of which the following is a specification.

This invention is an improvement in that 10 type of condenser in which a cooling liquid is delivered to and permitted to flow down through tubes traversing the space or chamber containing the fluid to be cooled, and relates more particularly to the means employed for distributing the cooling water supply and controlling the flow thereof to the tubes.

In its preferred form, my invention is an improvement on the construction shown and 20 claimed in my prior Patent Number 1,522,366, issued January 6, 1925. As one feature of the construction there shown, the tubular distributors which are inserted in the upper ends of the condenser tubes have 25 flow controlling passages at their lower ends leading to the condenser tubes and have their upper ends of reduced diameter. One object of this reduction in diameter is to permit the more ready flow of the water 30 from the supply conduit to the condenser tube farthest therefrom.

The main object of my present invention is to further regulate and control the distribution of the water or other cooling liquid so that the head of water and therefore the water pressure at the several distributors or controlling elements will be the same, and whereby the cooling effect will be rendered more uniform throughout the apparatus. In condensers of the type in which there are a plurality of vertical cooling tubes within a cylindrical shell, the innermost tubes are ordinarily farthest from the source of water supply and extend through 45 the point where the need for cooling effect is the greatest. As one important feature of my invention I secure the desired uniform water pressure and the desired cooling effect at the center of the condenser by varying the cross sectional area of the flow passages into the condenser tubes in accordance with the distance of said tubes from the source of water supply. As another important feature, I deliver the water preferably tangentially to an outer annular

chamber from which it may flow inward radially at a large number of points distributed about the circumference so that there will be uniform flow inward radially toward the center from all sides.

In the accompanying drawing, I have illustrated one embodiment of my invention which has proved very satisfactory in commercial use. Obviously other forms might be designed within the spirit of my invention without departing from the scope of the appended claims.

In the accompanying drawing,

Figure 1 is a top plan view of a condenser having a water distributing apparatus constructed in accordance with my invention,

Figure 2 is a vertical section of a portion of the upper part thereof on a larger scale,

Figure 3 is a perspective view of one of the water distributing tubes and

Figure 4 is a plan view of four tubes showing variation in the cross section of the flow passages to the tubes.

I have illustrated my invention in connection with a condenser having a cylindrical shell 10 provided with a flange 11 riveted to a head or tube sheet 12. Extending through the tube sheet and through the space or chamber of the condenser are a plurality of cooling tubes 13.

The head or tube sheet 12 is of larger diameter than the shell 10 and serves to support an annular wall 14 which, in connection with the head, forms a cooling water supply chamber 15 from which the water may be delivered to the several tubes 13.

Within the upper end of each tube, I provide a distributing member 16 which may be constructed substantially as shown in my prior patent above referred to. As shown, each distributor has a lower portion 17 adapted to loosely fit within the upper end of a corresponding condenser tube and a flange 18 for resting upon the end of the tube and supporting the distributing member. One or more water flow passages 19 lead in a helical direction through the flange 18 and the outer surface of the lower part 17 so that the water may flow from the chamber 15 through these passages to the inner surface of the condenser tube and be distributed in a downward and tangential direction so as to more effectively insure the complete covering of the inner surface of the tube by cooling water. Each member 16

is hollow so that the central passage, which is open at the top, may serve as an over flow outlet and the upper portion of each member 16 is of materially smaller diameter than the corresponding condenser tube so that there will be the maximum space between said upper portions of adjacent members 16, for the flow of water from the source of supply to the tube farthest therefrom.

Within the water chamber 15 and outside of the group of members 16, I provide an annular wall 20 which may be of approximately the diameter of the shell 10. It may be centered and located in any suitable manner, as for instance, by extending into a groove in the upper surface of the tube sheet 12. Wall 20 is of less height than the wall 14 and is provided with an annular row of slots 21 along its entire circumference at the lower edge and through which water may flow from the annular trough outside of this wall to the circular chamber inside. The water is delivered to the annular trough through one or more inlet conduits 22 which preferably have delivery nozzles extending tangentially so that there will be a flow along the trough and past the several slots 21, and the head of water will be maintained substantially uniform at the several slots and at all points around the trough.

The cross sectional area of the water flow passages 19 at the tubes nearest the center of the condenser is made materially greater than the corresponding passages to the tubes nearest the water supply, in other words nearest to the slots 21 through the wall, 20. This may be accomplished by making the same number of slots in all of the members 16 but making the slots wider in the members which are inserted in the tubes nearest the center, or it may be accomplished by making the slots uniform in size for all of the tubes and varying the number in accordance with the distance from the source of water supply. In the specific form illustrated, I vary the number of slots and keep the size of the slots uniform, although the other arrangement for maintaining a variation in the cross sectional area might be employed. The difference between the two extremes of cross section area may be varied according to the head of water to be maintained, the diameter of the condenser, the size of the passages and various other factors. For instance, the member 16 which goes into the centermost condenser tube and those closely adjacent to it, may have four of the water delivery slots 19, the next annular zone may have three such slots, the next outer zone two slots, and the outermost tubes may have only one. It will of course be understood that this variation from one to four is merely given as an example, for 65 the variation might be through a wider or

narrower range and the number of passages on even the outer row might be very materially greater.

In my improved construction it will be noted that the inlet ends of the passages 19 are above the tube sheet 12 and that the upper ends of the distributors are above the normal water level in the container. Thus any solid matter which is heavier than the water will settle and collect on the tube sheet 75 without clogging the passages 19, and any solid matter which is lighter than the water floats to the top, will stay there and remain above the ends of said passages. The passages will thus remain free and clear, and only very infrequent cleaning is necessary. If the water level be kept above the upper ends of the slots 21, the wall 20 will also serve to prevent any solid matter from floating to the portion of the water chamber directly adjacent to the passages 19. It will be noted that any one of the distributors may be very easily removed, cleaned and replaced without interfering with the operation of the condenser or necessitating the removal of any other distributor.

Having thus described my invention what I claim as new and desire to secure by Letters Patent is:—

1. A vertical tube condenser having an upper tube sheet, a plurality of tubes projecting downwardly therefrom, a wall coacting with the tube sheet to form a container for cooling liquid above the tube sheet, said condenser being provided with a plurality of distributors within said container, each distributor having a passage for the flow of water from said container to the interior of the corresponding tube, the cross sectional area of the passages of said distributors varying in accordance with the distance from the water inlet of said container.

2. The combination with a vertical tube condenser having a cylindrical shell, an upper tube sheet, a plurality of tubes projecting from said tube sheet through said shell, and a wall coacting with the tube sheet to form a container for cooling water above the tube sheet and a plurality of distributors within said container, each registering with a corresponding tube and each having a water flow passage from the lower portion of said chamber to the interior of the tube, the cross sectional area of the passages of the distributors nearest to the center of the condenser being greater than the area of the passages of the distributors nearest to the periphery of the condenser.

3. The combination with a vertical tube condenser having a cylindrical shell, an upper tube sheet, a plurality of tubes projecting from said tube sheet through said shell, and a wall coacting with the tube sheet to form a container for cooling water above

the tube sheet, and a plurality of distributors within said container, each registering with a corresponding tube and each having a water flow passage from the lower portion 5 of said chamber to the interior of the tube, the passages of all of said distributors being of substantially the same size and the distributors nearest to the center of the condenser having a larger number of said 10 passages than have the distributors nearer to the periphery of the condensers.

4. A vertical tube condenser having an upper tube sheet, a plurality of tubes projecting downwardly therefrom, an outer 15 wall coacting with the tube sheet, a container for cooling liquid above the tube sheet, an annular wall within said container, and spaced inwardly from said outer wall to form with the latter an outer trough, said 20 inner wall having openings therethrough along the length thereof adjacent to the tube sheet, a plurality of distributors within the space encircled by said inner wall and each communicating with its corresponding condenser 25 tube and each having a passage for the flow of water from the lower portion of said water chamber to the interior of the condenser tube, the cross sectional area of the 30 passages of the several distributors increasing as the distance of said distributors increases from said inner wall.

5. A vertical tube condenser having an upper tube sheet, a plurality of tubes projecting downwardly therefrom, an outer wall 35 coacting with the tube sheet to form a container for cooling liquid above the tube sheet, an annular wall within said container, and spaced inwardly from said outer wall to form with the latter an outer trough, said

inner wall having openings therethrough 40 along the length thereof adjacent to the tube sheet, means for delivering cooling water to said trough in a substantially tangential direction past said openings, a plurality of 45 distributors within the space encircled by said inner wall and each communicating with its corresponding condenser tube and each having a passage for the flow of water from the lower portion of said water chamber to the interior of the condenser tube, the 50 cross sectional area of the passages of the several distributors increasing as the distance of said distributors increases from said inner annular wall.

6. A vertical tube condenser having an 55 upper tube sheet, a plurality of tubes projecting downwardly therefrom, an outer wall coacting with the tube sheet to form a container for cooling liquid above the tube sheet, an annular wall within said container, and spaced inwardly from said outer wall to form with the latter an outer trough, 60 said inner wall having openings therethrough along the length thereof adjacent to the tube sheet, means for delivering cooling water to said trough in a substantially tangential direction past said openings, and a plurality of distributors within the space 65 encircled by said inner wall and each communicating with its corresponding condenser tube, and each having a passage for the flow 70 of water from the lower portion of said water chamber to the interior of the condenser tube.

Signed at Carbondale, in the county of 75 Lackawanna and State of Penna. this 29th day of April A. D. 1925.

NICOLAI H. HILLER.
